UNITED STATES PATENT OFFICE.

WILLIAM B. CLEVELAND, OF CLEVELAND, OHIO, ASSIGNOR TO THE ELECTRIC RAILWAY IMPROVEMENT COMPANY, OF CLEVELAND, OHIO, A CORPORATION OF OHIO.

APPARATUS FOR ELECTRIC WELDING.

1,290,089.

Specification of Letters Patent.

Patented Jan. 7, 1919.

Application filed April 23, 1915. Serial No. 23,510.

To all whom it may concern:

Be it known that I, WILLIAM B. CLEVELAND, a citizen of the United States, and a resident of Cleveland, county of Cuyahoga, 5 and State of Ohio, have invented a new and useful Improvement in Apparatus for Electric Welding, of which the following is a specification, the principle of the invention being herein explained and the best mode in 10 which I have contemplated applying that principle, so as to distinguish it from other inventions.

The present improvements relate more particularly to the welding together of metal 15 parts, or bodies, where such bodies are of unlike masses, and different temperatures of fusion, the smaller mass having both the lower temperature of fusion, and the greater conductivity, although neither the method 20 nor apparatus is necessarily limited to such particular application or field of use. More especially still, such improvements are adapted for the welding, or brazing, of bonds onto rails in accordance with the so-called "Herrick" process of making a homogeneous mechanical juncture, said process being described in United States Letters Patent No. 1,012,077, to Albert B. Herrick, dated December 19, 1911, whereby such 25 "bonding" is now satisfactorily accomplished with the aid of the electric current.

The welding electrode, which constitutes one of the distinctive features of the present apparatus, forms the subject matter of a 35 separate application filed by me October 16, 1909, Serial No. 522,921, the present invention consisting in a special mode of use of such electrode, involving the provision of certain accessory parts, and more especially 40 of a particular construction of support. As described and claimed in such co-pending application, said electrode consists, in effect, of two sections having contiguously disposed faces adapted simultaneously to contact with 45 the body being operated upon, and thereby close a series circuit through said electrode sections and body.

The aforesaid electrode sections are, furthermore, independently adjustable in the 50 means provided for supporting the same, so as to permit of such contiguous faces being held against the body being operated upon, with a relatively variable pressure, depending upon such adjustment, and thus enable a 55 predetermined heating effect to be secured

opposite such electrode sections, respectively. By means of the special supporting apparatus, which forms the subject matter of the present invention, I am enabled, in addition to the independent adjustment of the electrodes just referred to for securing a variable pressure, to provide for their simultaneous or conjoint adjustment to thus vary the pressure exerted by said electrode sections, respectively. To the accomplishment 60 of the foregoing and related ends, the invention, then, consists of the means hereinafter fully described and particularly pointed out in the claims.

The annexed drawings and the following 70 description set forth in detail certain mechanism embodying the invention, such disclosed means constituting, however, but one of various ways in which the principle of the invention may be used.

In said annexed drawings:—
Figure 1 is a perspective view of an approved form of my present apparatus, shown in connection with a portion of a truck, or like means of transport, and also showing 80 sections of two meeting rails, in conjunction with which the bonding operation is to be carried out; Figs. 1^a and 1^b are transverse sections of such apparatus taken on the planes indicated by the line 1^a—1^a, Fig. 1, and 1^b—1^b, Fig. 1^a respectively; Fig. 2 is a front elevational view of the electrode proper and its immediate supports; Fig. 3 is a top plan view of such electrode; Figs. 4, 5 and 6 are transverse sectional views of the 85 same taken on the lines 4—4, 5—5 and 6—6, respectively, Fig. 2; and Fig. 7 is a diagrammatic representation of the method or process involved in using the foregoing apparatus in welding a bond to a rail.

Referring to the perspective illustration of the complete apparatus constituting Fig. 1 of the drawings, it should be explained that such apparatus, in all of its main features, is identical with that forming the 100 subject matter of Patent No. 961,984, to W. A. Neff, dated June 21, 1910, so that the detailed illustration may be omitted of all features other than those of direct interest in the present connection.

As has been previously indicated, the apparatus is conveniently, but not necessarily, supported upon a truck, or platform car A, movable upon a track, the rails of which it is desired to bond. It is not meant to im- 110

ply, of course, that the apparatus is limited to use with any particular kind of a support. Of such rails, two meeting sections B, B are shown in Fig. 1, with the apparatus about to be described, in proper operative position with reference thereto, to attach one terminal of the bond b to one rail-end. Ordinarily, the current for carrying out such operation, will be derived from the trolley wire and return circuit usually found in connection with the track where the operation of bonding is to be conducted. In this event, suitable apparatus for transforming and converting the current, together with the necessary switches, circuit breaker, controller, resistance, and the like, are borne upon the car A. In the process intended to be carried out with the aforesaid Patent No. 961,984, the rail is intended to be utilized as a part of the return circuit, and the current used in bonding is hence passed in series through the heating electrode carried by one arm of the apparatus, the bond terminal and the rail, to the other electrode. In the present arrangement, as previously indicated, the current used in the welding operation is not intended to pass through the rail, but through the bond terminal only.

The supporting apparatus proper, comprises a plate, or member 1, formed with a transverse slide-way, rigidly secured to a corner of the car frame, so as to form, in effect, a part thereof. On this slide-way is mounted a second plate 2 formed, in turn, with a vertical slide-way 3 that bears a third member in the form of a plate 4, said plate 2 being moved transversely of the car by operation of a hand-wheel 5 having suitable threaded connection therewith, as will be readily understood. In conjunction with said plate 2, thus transversely slidable, there is provided a vertical shaft, or rod 6, disposed in front of, and parallel with, the slide-way 3 therein, on which the vertically slidable plate 4 is movable. The latter is formed with suitable apertured ears through which the rod may pass, and is longitudinally secured thereto, so that raising or lowering of the rod will be effective to raise or lower said plate 4 relatively to the plate 2 together with a block-like casting 7 that is, in effect, pivotally attached to said member by said rod so as to be oscillatory about the substantially vertical axis defined by the latter.

Member 7, thus oscillatorily mounted about a vertical axis, and vertically and transversely adjustable, as well, by reason of the construction just described, is provided on its sides with vertical slide-ways 8 and 9, in which are respectively held slide-members 10 and 11 that may be adjusted into any desired position relatively to said first member, by means of hand-wheels 12 and 13.

To these slides are in turn respectively pivotally attached about transverse axes, two links 14 and 15 which serve to support the electrode members 16 and 17 proper. Of these, the latter in the present case, constitutes in effect, merely a clamp member, no current being passed therethrough and may be omitted entirely if desired; while the other does not directly contact with the article to be welded, but carries the heating electrode the specific construction of which will be now duly set forth.

Before proceeding with such specific description of the heating electrode proper, it should be observed that the two members 16 and 17 are adapted to be swung inwardly or outwardly from their linked connection with the block 7, by means of hand-wheels 19 and 20 on threaded spindles, or adjusting screws 21 and 22. The inner ends of 85 the latter engage an extension 23 on the shaft 6, which is provided with suitable slidable connections for such screw ends, so as not to interfere with the free vertical adjustment of the electrode members. As a 90 result of the construction of the parts thus far described, it will be seen that the members 16 and 17, and more particularly the former which supports the heating electrode proper, may not only be moved in a 95 vertical and transverse direction with reference to the line of the rail, but also that such electrode may be oscillated about a vertical axis defined by the shaft 6, such oscillation being effected by means of a hand-wheel 25 on a threaded spindle 26 rotatably mounted in the member 7, but held against longitudinal movement therein, and having threaded engagement with a swiveled stud 27 mounted on the vertically slidable 105 plate 4.

The heating electrode proper, as best shown in Fig. 2, comprises two depending arms 30, 31, which are suitably secured to the member 16, being insulated from each 110 other and from said member. To thus mount said arms, they are preferably pivotally attached at points intermediate between their ends, as by bolts 32, to the respective ends of a short bar 33 which is either constructed 115 of insulating material or else is suitably insulated from said arms by other means, such as interposed layers 34 of insulation, as illustrated in Fig. 6. The lower end of the member 16 then is rigidly bolted to this bar, preferably on the opposite side from that to which said arms are thus pivotally attached. Accordingly the movement of the member, whether vertically, transversely or oscillatorily, will be communicated to the arms and to whatever parts are in turn supported thereby.

The upper ends of the respective arms are provided with offset portions 35 and 36 to facilitate the connections therewith of inde- 130

pendent electric conductors 37 and 38 whereby said arms may be included in an electric circuit.

As a result of the pivotal connection of the 5 arms 30 and 31 to the bar 33, they are obviously rendered relatively movable, and for effecting such movement a screw 39 is provided connecting their upper ends, being rotatably mounted in one such arm so as to be held 10 against longitudinal movement, and having threaded engagement with the other. An insulated bushing 40 or equivalent means, is provided in order to maintain the arms electrically separate and said screw is desirably 15 provided with a hand-wheel 41 for convenience in operation. Upon drawing the upper ends of the two arms toward each other by rotating said hand-wheel and screw in the proper direction, the lower ends of 20 said arms may be moved away from each other in the plane of the drawing in Fig. 2; while by rotating said screw so as to force such upper ends of the arms apart, the lower ends thereof will conversely be moved 25 toward each other.

Suitably attached to each of said arms 30 and 31, as by bolts 45, is a clamp member 46, to which in turn is attached, as by means of a bolt 47, a complementary clamp member 30 48, thus providing a separate set of such clamp members 46, 48, on each arm. The latter are adapted to receive corresponding electrode sections 50, consisting of two entirely 35 separate pieces of carbon or other suitable high resistance material. To assist the bolts 47 in operating the respective sets of clamp members to secure such electrode sections in place, two set-bolts 51 are provided, the same being threaded in ears 52 projecting laterally from the respective clamp members 46 and adapted to press with their ends against alined ears 53, respectively laterally projecting from the other clamp members 48.

45 By reason of the construction of the clamp members, as just described, not only are the electrode sections 50 detachably secured therebetween so as to be interchangeable and thus permit a fresh electrode to be substituted for one that has become worn out or deteriorated, but such sections or individual blocks, may also be independently moved in a direction transverse of their forward faces 54 (Fig. 3), or at right angles 50 to the plane of the drawing in Fig. 2, in order to permit the forward adjustment of said blocks as the latter wear away, and thus insure that said blocks will respectively contact with the desired degree of pressure 55 against the body being operated upon, as will be presently described. In order to loosen the electrode sections so as to permit the same to be either removed or adjusted, as above described, it will ordinarily be 60 sufficient to turn the screws 51, so as to relieve

the clamping pressure of the lower clamp members 48; but if this is not sufficient, the nuts on the bolts 47 may also be loosened, without it, however being necessary to detach said clamping members.

70 The electrode sections or blocks 50 are preferably so disposed between the respective sets of clamp members 46, 48, or else are so shaped as to bring the forward edges of said blocks closer to each other than the rear edges thereof and thus cause such forward edges to contact as will be readily understood, when the lower ends of the arms 30, 31 are forced together by operation of the screw 39, while leaving an air space between the remainder of their juxtaposed faces, which serves to electrically separate the two blocks, save at such forward edges. By operating said screw in the reverse direction, so as to move the lower ends of said 85 arms apart, the blocks may be entirely separated. The forward faces of said blocks, whether the latter are thus brought into partial contact or entirely separated, lie in substantial alinement as shown in Figs. 3 90 and 4, and are contiguously disposed, being so formed as to fit the bond terminal, or other body upon which it is desired to operate.

95 In utilizing the foregoing apparatus, the electrode sections or blocks 50 are preliminarily brought together in the manner previously described, thus closing the electric circuit through the conductors 37, 38, and the arms 30, 31, said blocks being retained in such contact for a sufficient length of time to bring them to a relatively high temperature before their contact faces are approached to the bond terminal, or other article to be welded. This preliminary heating effect will of course be most pronounced in the portions of the electrodes nearest the contacting edges thereof, that is in the portions bounded by the contiguous contact faces of the blocks. Upon now pressing 100 such contact faces of the electrode sections against the bond or other body to be heated, even if the edges of such sections be left in contact, by far the larger volume of current will bridge its way across from the 110 one section to the other through the bond, this being the path of least resistance. The faces of the blocks are thus brought to and retained at the desired high temperature and at the same time the heating effect of 115 the current in passing through the adjacent portion of the bond, or other body, owing to the element of resistance which the latter provides, will assist in bringing such body to the desired temperature for welding or 120 brazing. Where such body is a bond, and the result to be accomplished is the welding or brazing of the latte, to a rail, the heat generated in the electrode sections and in the bond passes by conduction to the contacting 125 130

- face of the rail or other second body, and the latter is brought to the proper temperature for the desired operation, practically simultaneously with the first body.
- 5 By means of the foregoing construction of electrode, I provide electrically a source of heat that may be handled much as a torch or blow pipe in the manner in which it may be brought up to the body to be operated upon.
- 10 It will be understood that were an integral block of carbon simply interposed in the circuit, it would be difficult to raise the exterior surface thereof, designed for contact with the bond, to the necessary temperature.
- 15 By using, however, two separate carbons and bridging the current from one to the other through one of the bodies being operated upon in the manner described, the contiguously disposed contact faces of both
- 20 carbons are readily maintained in desired incandescent state.
- Supplementary to and independent of the variation in the pressures exerted by the respective electrode sections, which may be
- 25 secured by initially adjusting the same in their respective clamps at the lower ends of the arms 30, 31, such pressures may be varied by oscillating the block 7 about the vertical axis defined by the rod or shaft 6,
- 30 thereby, at the same time, oscillating the member 16 and the two electrode sections, so as to increase the pressure exerted by the one and simultaneously decrease the pressure exerted by the other. This variation
- 35 in the pressures exerted by the electrode sections, may of course be produced while the welding operation is under way, and may be used to modify the predetermined heating effect which the electrode sections,
- 40 as initially set, would produce. In other words, by reason of this particular method of mounting my improved dual electrode, I am enabled to obtain this additional adjustment for varying, during the course of the
- 45 operation, the relative pressures exerted by the two electrode sections. Difference in the heating effect produced by the two sections in the adjacent portions of the bond or other body being operated upon, may thus
- 50 be compensated for and such heating effect equalized so as to bring the entire body to the proper temperature for uniting the same to the other body, whether the union be considered a braze or a weld.
- 55 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the class described, of
- 65 the combination with supporting means; of

two heating electrodes carried thereby and having contiguously disposed faces adapted simultaneously to contact with the body being operated upon and thereby close a series circuit through said electrodes and body, said electrodes being conjointly oscillatory to vary the pressures exerted by such faces, respectively.

2. In mechanism of the class described, the combination with supporting means; of

70 two heating electrodes carried thereby and having contiguously disposed faces adapted simultaneously to contact with the body being operated upon and thereby close a series circuit through said electrodes and body, said electrodes being conjointly oscillatory in a plane transverse to their contact faces to vary the pressures exerted by such faces, respectively.

3. In mechanism of the class described, the combination with supporting means; of

75 two heating electrodes carried thereby and having contiguously disposed faces adapted simultaneously to contact with the body being operated upon and thereby close a series circuit through said electrodes and body, said electrodes being independently relatively movable in a direction transverse of their contact faces and also conjointly oscillatory, whereby the pressures exerted by such faces may be varied.

4. In mechanism of the class described, the combination with supporting means; of

80 two heating electrodes carried thereby and having contiguously disposed faces adapted simultaneously to contact with the body being operated upon and thereby close a series circuit through said electrodes and body, said electrodes being independently relatively movable in a direction transverse of their contact faces and also conjointly oscillatory in a plane transverse to such faces, whereby the pressures exerted by such faces may be varied.

5. In mechanism of the class described, the combination with a suitable support; of

85 a member, mounted thereon so as to be oscillatory about a substantially vertical axis; two heating electrodes carried by said member, said electrodes lying in a horizontal

90 plane and having contiguously disposed faces adapted simultaneously to contact with the body being operated upon and thereby close a series circuit through said electrodes and body; and means adapted to adjust said member about its axis to vary the pressures exerted by such faces, respectively.

6. In mechanism of the class described, the combination with a suitable support; of

95 a depending member, mounted thereon so as to be oscillatory about a substantially vertical axis; two relatively movable arms attached to said member and insulated from each other; clamping means borne by each arm; a block of high resistance material se-

100

cured to each such clamping means, said blocks lying in a horizontal plane and having contiguously disposed faces adapted simultaneously to contact with the body being operated upon and thereby close a series circuit through said blocks and body; means adapted to move said arms and thus said blocks toward and away from each other; and other means adapted to adjust said member about its axis to vary the pressures exerted by such faces, respectively.

7. In mechanism of the class described, the combination with a suitable support; of a depending member, mounted thereon so as to be oscillatory about a substantially vertical axis; two relatively movable arms attached to said member and insulated from each other; clamping means borne by each arm; a block of high resistance material se-

cured to each such clamping means, said blocks lying in a horizontal plane and having contiguously disposed faces adapted simultaneously to contact with the body being operated upon and thereby close a series circuit through said blocks and body, and said blocks being adjustable in said clamping means transversely of such contact faces; means adapted to move said arms and thus said blocks toward and away from each other; and other means adapted to adjust said member about its axis to vary the pressures exerted by such faces, respectively.

Signed by me, this 22nd day of April, 1915.
